F. A. BROWN

DEVICE FOR HANDLING WIRE CONNECTERS

Filed April 23, 1923

FIG. 1.

FIG. 2.

Patented Nov. 8, 1927.

1,648,635

UNITED STATES PATENT OFFICE.

FRED A. BROWN, OF LOS ANGELES, CALIFORNIA.

DEVICE FOR HANDLING WIRE CONNECTERS.

Application filed April 23, 1923. Serial No. 634,169.

This invention relates to a device for handling wire connecters to apply them, and it is an object of the invention to provide a simple, effective, and reliable device of this 5 character.

In numerous situations it is desirable to connect with a power line, or the like, without deenergizing it. For instance, where power lines run through agricultural districts it often becomes necessary to connect take-off lines with the power lines to operate pumping plants, etc. In a situation of this kind it is very detrimental and inconvenient to kill the power line in order to 10 make a connection as this means that operation is stopped at all points supplied by the power line.

For the purpose of making connections as quickly as possible and thereby reducing the 20 time necessary to make the connections of the character above mentioned, connecters have been developed which clip the wires together quickly so that they remain connected until such time as it is convenient to 25 make a permanent connection.

It is an object of this invention to provide means for holding a wire connecter, such as I have just referred to, so that it can be applied to an energized line without danger to 30 the operator.

Another object of this invention is to provide jaws which can be applied to a device such as is commonly known as a fuse grabber to make it suitable for handling a wire 35 connecter.

The various objects and features of the invention will be best and more fully understood from the following detail description of a typical preferred form and application 40 thereof, throughout which description reference is had to the accompanying drawings, in which:

Fig. 1 is a side elevation showing a device embodying the present invention holding a 45 typical wire connecter in position ready to be applied to a wire;

Fig. 2 is a rear elevation of the device, shown in Fig. 1, being a view taken as indicated by the line 2—2 on Fig. 1;

Fig. 3 is a side elevation of the wire connecter alone;

Fig. 4 is a detail sectional view, taken as indicated by the line 4—4 on Fig. 1; and

Fig. 5 is a detail sectional view, taken as 55 indicated by line 5—5 on Fig. 4.

In the drawings, numeral 10 designates,

generally, a wire connecter, numeral 11 a carrier, and numeral 12 jaws arranged in the carrier so that it will hold the connecter 10. The wire connecter which I have chosen 60 to illustrate in the drawings includes a main part 13, a jaw 14 pivotally connected with the main part, and a spring 15 arranged in combination with the main part and jaw 14 so that they are normally yieldingly held 65 together in a manner to grip a wire, or the like. The main part 13 of the connecter 10 has a jaw portion 16, which is comparatively broad and faces the jaw 14; a socket 17 at the outer end of the jaw portion 16; a 70 rib 18 extending from the rear of the jaw portion 16; and a flange part 19 at the inner end of the jaw portion 16 and extending transversely of the jaw portion 16. The socket 17 has an opening 20 adapted to receive the end portion of a suitable wire 21 and carries a screw 22 for setting the end of the wire in the opening. The rib part 18 extends between the jaw portion 16 and flange 19, as I have clearly illustrated in the various figures of the drawings, and there is an opening 23 extending through the rib 18 at the corner formed by the jaw portion 16 and flange 19. There is an indentation or groove 24 provided across the face of the jaw portion 16 to receive the wire on which the connecter is arranged. The jaw 14 is pivotally connected on a lug 25, which extends from the main part 13, so that it is opposite the jaw portion 16 of the main part 13 and 80 operates to hold the wire in the groove 24. 85 The outer portions of the jaw portion 16 and jaw 14 diverge so that the device can be readily arranged on a wire so that the wire enters the groove 24 and is retained therein 90 by the jaw 14. The spring 15 is arranged between the inner end portion of the jaw 14 and a lug 27 extending from the outer end 95 of the flange 19. The spring 15 operates to normally yieldingly hold the parts in the 100 position clearly illustrated in Figs. 1 and 3, so that the jaw 14 will operate to retain a wire in the notch 24. It is to be understood that this form of wire connecter is merely typical of the character of device or 105 devices that may be handled by the means provided by the present invention, and that the present invention is not, therefore, to be considered limited in any way to this or any other specific form of wire connecter.

The carrier 11, which I have illustrated in the drawings, is in the form of a device

commonly known as a fuse grabber. It includes a handle part 30, a pair of arms 31 pivotally connected with the outer end of the handle part 30, and means 32 for operating the arms so that they will grip an object. The handle 30 is formed of wood or other suitable insulating material, and is made sufficiently long so that the arms 31 are substantially removed from a person handling the device from the inner end of the handle. The operating means 32 shown in the drawings, includes an operating rod 34 which is slidably carried parallel with the handle 30 by guides 35, and two fingers 36 pivotally connected with the rod 34 and having sliding connection with the arms 31. The outer portions of the fingers 36 which engage the arms 31 are normally yieldingly held together by a spring 37. When the operating rod 34 is moved longitudinally of the handle 30 the outer portions of the fingers are moved along the arms 31. The arms 31 are more or less bowed or cam shaped so that they move toward each other when the fingers are moved outwardly. When the arms are thus moved toward each other they will, of course, grip an object with force equal to the strength of the spring 37. The operating rod 34 is made of non-conducting material, and extends to the inner end of the handle 30 so that the arms may be operated from said end of the handle. Devices of the character that I have just described are in more or less common use for handling fuses, and the like, and are commonly known as fuse grabbers. The present invention, however, is not specifically concerned with the exact details of arrangement and construction of the carrier, it being important only that the carrier have the general characteristics necessary to operate the jaws 12 in the manner hereinafter described.

The jaws 12 provided by the present invention, are adapted to be detachably mounted on the outer ends of the arms 31. Each jaw 12 includes a body part 40 and a shank 41. The shanks 41 are adapted to extend through openings 42 provided in the outer end portions of the arms 31, and wing nuts 43 are adapted to be screw threaded onto the outer ends of the shanks 41 to retain the jaws on the arms. The abutting faces 40^a of the body portions 40 and arms 31 are preferably corrugated or otherwise roughened so that the jaws are securely held against rotation when the wing nuts are made tight. With this construction, however, the jaws can be very easily and quickly arranged on or removed from the arms and can be readily adjusted as to their rotative position. The body portions 40 of the jaws 12 are designed and proportioned so that they will grip a suitable portion of the connector 10 when the arms 31 are moved to-

gether, and, further, so that they engage the connector 10 in a manner to hold it rigidly and against rotation as shown in Fig. 5. In accordance with the preferred form of the invention the body portions of the jaws 70 are made to grip the rib 18 and one of them is provided with a lug or extension 45 which extends into the opening 23 formed in the rib 18. The lug 45 in extending into the opening 23 causes the connector to be positively held by the jaws. Each of the body parts 40 of the jaws is formed with a flat portion 50 adapted to engage the jaw portion 16 of the connector and a flat portion 51 adapted to engage the flange 19. When 80 the jaws are in engagement with the connector 10 so that the lug is in position in the opening 23 the flat portions 50 and 51 are seated in engagement with the jaw portion 16 and flange 19 in the manner clearly illustrated in Figs. 4 and 5. The flat portions 50 and 51 operate to hold the connector against rotation relative to the jaws and so that it is particularly firm or rigid. The body portions 40 are provided with shoulders 52 at the inner ends of the flat portions 50 and 51 to engage the edges of the jaw portion 16 and flange 19 to further prevent movement of the connector while it is held by the jaws.

In operation, when it is desired to connect a wire 21 with an energized wire by means of a connector 10, the connector 10 is mounted on the arms of a carrier 11, such as I have hereinabove described, the arms of the carrier being closed on to the connector so that the connector is gripped and held by the jaws 12. The carrier 11 is then manipulated by means of the inner end of the handle 30 so that the connector is arranged on the energized wire so that the wire is carried in the notch 24 and is held therein by the jaw 14. The arms 31 are then released by actuation of the operating means 32 so that the jaws 12 release the connector 110 and leave it connected on the energized wire. It will be obvious that this operation can be very easily and quickly carried out and that it can be done with perfect safety, even though wire to which the connector is applied is energized. In practical operation connectors of this character have been applied to wires carrying as high as fifteen thousand volts. In practice it is desirable, of course, to have the connector 10 carried in different positions by the carrier so that it can be mounted on a wire in the most advantageous manner. With the jaws 12 adjustably mounted on the arms 31 in the manner hereinabove described they can be 120 rotated so that the connector 10 is carried in any desired position with relation to the arms 31. Whenever it is desired to use the carrier 11 for handling fuses, or the like, the jaws 12 can be easily and quickly removed 130

by removing the wing nuts and withdrawing the shanks 41 from the openings 42. A distinctive feature of the present invention is that the jaws 12 are comparatively small and are applicable to a device such as a fuse grabber to make it suitable for handling a wire connector 10, thus making it unnecessary to have a complete special tool for handling the connectors in addition to the tools for handling fuses.

Having described only a typical preferred form of my invention I do not wish to limit myself to the specific details hereinabove set forth but wish to reserve to myself any changes or variations that may appear to those skilled in the art or fall within the scope of the following claims:

Having described my invention, I claim:

1. An attachment for a wire connector carrier, the carrier having pivotally connected arms, including a pair of jaws adapted to be mounted on the arms to hold the connector, the jaws including a part for positively holding the connector and parts for engaging the connector to hold it rigidly.

2. An attachment for a wire connector carrier, the carrier having pivotally con-

nected arms, including jaws adapted to be mounted on the arms to hold the connector, the jaws having shanks by which they are attached to the arms and body portions with parts shaped to fit and positively and rigidly hold the connector.

3. An attachment for a wire connector carrier, the carrier having pivotally connected arms and the connector having an opening, including jaws to be mounted on the arms, a projection on one jaw to engage the opening in the connector, and parts on the jaws engaging the connector to hold it rigidly.

4. An attachment for a wire connector carrier, the carrier having pivotally connected arms and the connector having flat parts and an opening, including jaws to be mounted on the arms, a projection on one jaw to engage the opening in the connector, and flat parts on the jaws engaging the connector to hold it rigidly.

In witness that I claim the foregoing I have hereunto subscribed my name this 31st day of March, 1923.

FRED. A. BROWN.
